Nevil V. Dyer
By his Attorney,
Nelson M. Ward

UNITED STATES PATENT OFFICE.

NEWELL V. DYER, OF HOLBROOK, MASSACHUSETTS, ASSIGNOR TO UNITED SHOE MACHINERY CORPORATION, OF PATERSON, NEW JERSEY, A CORPORATION OF NEW JERSEY.

SKIVING-MACHINE.

1,342,430.

Specification of Letters Patent.

Patented June 8, 1920.

Application filed December 13, 1918. Serial No. 266,582.

To all whom it may concern:

Be it known that I, NEWELL V. DYER, a citizen of the United States, residing at Holbrook, in the county of Norfolk and

5 State of Massachusetts, have invented certain Improvements in Skiving-Machines, of which the following description, in connection with the accompanying drawings, is a specification, like reference characters on 10 the drawings indicating like parts in the several figures.

This invention relates to skiving machines and is herein illustrated as embodied in a machine for cutting off the end of a vamp 15 on an incline so that the finished end of the vamp will be beveled.

In the manufacture of boots and shoes 20 in which square-ended or cut-off vamps with tips stitched to them are used, it is customary in many factories to cut the vamps from patterns which are correct for the shortest tips to be used, the tips being of various lengths. The square end of the 25 vamp is skived in any event so as to prevent the formation of an objectionable bunch or rib along the locality of its attachment to the tip; and in the case of a long tip where the extent of the overlap would be objectionable it is customary to 30 shorten the vamp by cutting a strip from the end thereof and then to skive the end.

The general object of the present invention is to provide a machine by the use of which the cutting off and skiving operation 35 may be performed upon a vamp or other article of similar flexible material. To this end one feature of the invention relates to work supporting and feeding means comprising a rotary supporting and 40 feeding roll and a stationary supporting member upon which the work is held by a presser foot while being advanced to the knife. By cutting away the stationary member in the rear of the presser foot to 45 provide a proper space, the knife may be inclined sufficiently to sever the work on an angle and at the same time may have its edge located close to the locality at which the work is engaged by the presser foot so 50 that no bulging or wrinkling of the work occurs between the foot and the knife.

This and other features of the invention including certain details of construction and combinations of parts will be described as

embodied in an illustrative machine and 55 pointed out in the appended claims.

Referring now to the accompanying drawings,—

Figure 1 is an elevation of a portion of a machine in which the present invention is 60 embodied, and

Fig. 2 is a plan of the stationary supporting member viewed from a point in the extended axis of the screw 15.

The machine chosen for illustration is 65 of the "Amazeen" type and is or may be identical in many respects with the machine shown and described in the patent to Bayley No. 823,578. The machine comprises a feed roll 3 having a cylindrical portion 5 70 of reduced diameter with which the margin of a feed disk 7 coöperates to aid in feeding the work. A presser foot 9 holds the work down upon the knurled surface of the feed roll as well as upon that of a stationary 75 member, presently to be described, and a rotary disk knife 11 is located behind the foot, its cutting edge being inclined to the axis of rotation of the feed roll. The shafts 12, 14 and 16 of the roll, knife and feed 80 disk respectively may be rotated by any suitable mechanism such, for example, as that shown in the patent, and in general the parts which have thus far been described with the exception of the presser foot may 85 be like the corresponding parts of the patented machine and similarly mounted for adjustment.

The patented machine is adapted to skive the margin of a piece of flexible material 90 such as a vamp. It is not practicable, however, to sever a piece of material upon the machine for the reason that the operative portion of the edge of the knife should run close to the locality at which the work 95 is held down upon the roll by the presser foot, since otherwise the work is liable to wrinkle and thereby be cut irregularly. It is therefore necessary to keep the effective edge of the knife so close to the locality at 100 which the work is gripped between the roll and presser foot that before the knife can be tilted sufficiently to sever the work it will contact with the roll.

In order to obviate this difficulty a stationary supporting member 13 is provided 105 to support that part of the work which is to be cut off. This member is fastened to the

bearing of the roll by a screw 15 and has an operative surface which is curved and forms a continuation of the work supporting surface of the roll. This member extends beneath the presser foot 9, and its rear end is cut away as indicated at 17 on a curve which is concentric with that of the edge of the knife, the curved end being also undercut, as indicated by the dotted line 19 so that the edge of the knife may run just underneath the overhanging end of the supporting member. With such a construction the knife may be tilted as shown about a horizontal line extending approximately through the uppermost point of junction of the surface of the roll 3 with that of the stationary member 13 without contacting either with the roll or with the stationary member; and at the same time the forward point on the cutting edge of the knife may lie, as it should, close to the locality at which the rear edge of the presser foot engages the work.

The presser foot 9 overlies both the roll and the stationary supporting member and is mounted in the usual manner upon an adjustable bracket 21. The edge gage 23 is fastened by a screw 25 to a rectangular bar 27 which is slidable in a guideway in a stationary lug 29 formed upon a plate 31. This plate is adjustable toward and from the feed roll on a second plate 33, which in turn is adjustable on the bracket 21 in a direction transverse to the axis of the feed roll, the two plates having formed respectively in them slots (not shown) which are at right angles to each other and through which passes the stem of a screw 35 by which the plates are held in adjusted position. At its right-hand end the bar 27 is fastened by a screw 37 to a sliding block 39. An adjusting screw 41, which is threaded through the block 39, has a reduced portion extending through a bore in the lug 29, a nut 43 being threaded on the projecting end of said reduced portion. The screw is thus held from longitudinal movement so that when it is turned by manipulating the knurled head 45 the edge gage 23 is adjusted to the left or to the right to decrease or increase the width of the strip which will be cut off from the end of the vamp.

In the operation of the machine the knife is adjusted to the proper angle, such for example as the one shown, with the plane of its cutting edge intersecting approximately the vertical plane at the junction of the roll 3 and the member 13 at a point in the path of the work. The edge gage is then adjusted by turning the screw 45 to regulate the width of the strip which is to be cut off. The square end of a vamp is then placed against the gage and pushed sidewise beneath the presser foot 9 and the feed disk 7, whereupon it is fed to the knife, the main portion

of the vamp passing under the knife and the piece or strip which is cut off passing over the knife.

Although the invention has been set forth as embodied in a particular machine, it should be understood that the invention is not limited in the scope of its application to the particular machine which has been shown and described.

Having thus described my invention, what I claim as new and desire to secure by Letters Patent is:

1. A machine for cutting on an angle a strip from a piece of flexible material, having in combination, a rotary feed roll for engaging the body of the material, a stationary member for supporting the portion which is to be cut off, said member having an operative face curved to correspond to the curvature of the feed roll, and a knife inclined to the axis of the roll.

2. A machine for cutting on an angle a strip from a piece of flexible material, having in combination, a rotary feed roll for engaging the body of the material, a stationary member for supporting the portion which is to be cut off in substantially the same plane as the body portion, and a rotary disk knife the plane of the edge of which intersects the stationary supporting member.

3. A machine for cutting on an angle a strip from a piece of flexible material, having in combination, a work support comprising a rotary roll and a stationary member the operative face of which is curved to correspond to the curvature of the roll and forms an extension of the adjacent surface of the roll, means for rotating the roll to feed the work, means for pressing the work down upon the work support, and means for severing the work on an angle.

4. A machine for cutting on an angle a strip from a piece of flexible material, having in combination, work supporting and work feeding means comprising a rotary supporting and feeding roll and a stationary supporting member, and means for severing the work on an angle along a line which passes approximately through a point of junction of the surface of the roll with that of the stationary support.

5. A machine for cutting on an angle a strip from a piece of flexible material, having in combination, work supporting and work feeding means comprising a rotary supporting and feeding roll and a stationary supporting member curved to correspond to the curvature of the roll, and a knife inclined to the axis of rotation of the roll and having a portion extending below the uppermost portion of the stationary member.

6. A machine for cutting on an angle a strip from a piece of flexible material, hav-

ing in combination, a cutter, work supporting and work feeding means comprising a rotary supporting and feeding roll and a stationary supporting member, and means 5 for pressing the work against said roll and member.

7. A machine of the class described, having in combination, a work supporting and feeding roll, means for rotating the roll, a 10 stationary work support located at one end of the roll and having a curved surface which forms an extension of the adjacent surface of the roll, a presser foot adapted to hold the work against the roll and support, 15 said support being cut away adjacent the foot to provide space for a knife, and a knife located to sever the work on an angle along a line which passes approximately through a point of junction of the surface 30 of the roll with that of the stationary support.

9. A machine for cutting a strip from the toe end of a vamp, having in combination, a rotary feed roll, a stationary support adjacent to one end of the roll and having a supporting surface curved to correspond to the curvature of the roll, and a rotary disk knife located to coöperate with said roll and support to sever the vamp on a bevel. 35

In testimony whereof I have signed my name to this specification. 40

NEWELL V. DYER.
